UNITED STATES PATENT OFFICE

2,536,633

ANTITHUMB-SUCKING DEVICE

Robert F. Fitch, Glendale, Calif.

Application March 15, 1948, Serial No. 14,865

2 Claims. (Cl. 128—133)

1

My invention relates to a thumb guard for use by or on infants and small children to prevent or break a habit of thumb-sucking.

It has long been recognized that thumb-sucking if continued for too long a period results in malformation of a child's mouth and other serious psychological disturbances. Satisfactory methods for preventing such habits have long been sought.

Numerous devices have been patented and manufactured with such a purpose in mind. Such endeavors have taken the form of unpleasant tasting liquids applied to the thumb or metal, and plastic or fabric guards put over the thumb of the infant and tied around the infant's wrist.

Such mechanical devices are based on the theory that if it is impossible for the child to form a substantial vacuum between his thumb and lips, he will not suck his thumb. Such devices have proven unsatisfactory in that the infant either soon learns to remove the objectionable device or transfers his sucking tendencies from the thumb to the first index finger. It is, therefore, one of the objects of my invention to provide a thumb-sucking guard which is impossible for small infants to remove and which prevents sucking of both the thumb and the first index finger.

It has been recognized by eminent child psychologists that awkward devices attached to the hand prevent proper development of the use of the hand and may be as serious in its consequences to the personality development of the child as unabated thumb-sucking. It is also among the objects of my invention to provide a mechanical guard adapted to prevent sucking of either thumb or index finger which permits substantial freedom of movement of the infant's hand so that development of its use will not be retarded.

Other and further objects and advantages of my invention will become apparent from the drawings and the specifications relative thereto.

In the drawings:

Figure 1 is an isometric view of a thumb guard embodying the principles of my invention and illustrating its use.

Figure 2 is a partial cut-away side view of the device shown in Figure 1.

Figure 3 is a view taken on line 3—3 of Figure 2.

My invention comprises essentially an index finger envelope 10 and a thumb envelope 11. As shown in Figure 1, the envelopes 10 and 11 are tubular in form and are joined together at 12. The method of joining is optional in that the parts may be made integral, such as by injec-

tion molding of plastics, or can be made by joining independent tubes or envelopes with cement or suitable adhesive, the important feature being that the two tubes are secured together so that the thumb envelope 11 cannot be pulled off the thumb without also removing the index envelope 10 from the index finger. As will become apparent later, the removal of the index envelope 10 is substantially more difficult than the removal of the thumb guard 11.

The top 15 of the index envelope 10 and the top 16 of the thumb envelope 11 are illustrated as being substantially flat and square with respect to the axis of the tubular members. The configuration of this top is not especially important. It will be noted, however, that the bottoms 17 and 18 are cut on an angle oblique to the axis of the tubular members. This is necessary for the following reasons. The index tube 10 should be short enough that a portion of the index finger extends therethrough, and the thumb envelope 11 should also be short enough so that a portion of the thumb may extend therethrough. It is a matter of common knowledge that on an infant's hand if the thumb is to extend through the thumb envelope, the top of the thumb envelope will be below the juncture of the index finger and the palm of the hand. Therefore, in order to join the thumb and index envelopes, a portion of the index envelope must extend below the juncture of that finger. The opposite side, of course, cannot extend downwardly to this position without cutting into the hand between the index and middle fingers.

If the thumb envelope 11 did not extend downwardly below the joint of the thumb, it would be relatively easy for the child to slip a small ring or guard off the thumb.

Whereas, the preferred embodiment of my invention permits the extension of the index finger and thumb through the tubular members, such is necessary only if it is desired to permit some use of the thumb and index finger. The most important feature of the invention resides in the fact that the index finger and thumb guard are joined together so that the infant is prevented from removing either, thereby preventing sucking of the thumb or index finger, and I would consider a longer envelope which completely encloses the index finger and thumb a substantial equivalent of this objective.

The lower extremity of the thumb envelope is formed with a slot 20 through which is disposed a ribbon 21. The ribbon 21 is adapted to be tied around the infant's wrist to prevent re-

2

moval of the thumb guard. As was pointed out earlier, mechanical thumb guards which are used alone have proven unsatisfactory because even though a ribbon, such as 21, is tied around the infant's wrist, the infant has still been able to remove the guard from his thumb.

To prevent this, the upper extremity of the bottom portion 17 is formed with a slot 22 through which a ribbon 23 is inserted. After the ribbon 21 is tied around the infant's waist, the ribbon 23 extends down the back of the infant's hand and ties under the loop of the ribbon 21. It, therefore, becomes practically impossible for the infant to remove the thumb guard.

In order to provide or to permit a freer use of the infant's fingers and thumb and to further avoid the possibility of cutting into the infant's hand, I have provided a modified form, as is shown in Figures 4 and 5. The form, as illustrated, comprises a thumb envelope 30 and an index finger envelope 31 formed (as shown in Figure 5) of a continuous sheet of flexible plastic having the outer end margins 30a and 31a folded inwardly and secured to the center line, thereby forming the envelopes. The means of securing can be either by stitching, cementing or welding. The envelopes are pierced on the center line to form a slot 32 through which a wrist band 33 is inserted. The wrist band 33 is formed with a snap fastener having cooperating parts 34 and 35.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices. Having described my invention, what I claim as new and desire to secure by Letters Patent is:

1. An anti-thumbsucking device comprising a

index finger of an infant's hand, said tubes being secured together, said tubes having lower edges forming a continuous unbroken curved line adapted to fit the contour of the hand to permit free movement of the joints of the thumb and index finger, each of said tubes being formed with an aperture adjacent one end thereof and oppositely disposed, adapted to receive means for tying the said device to the hand of the infant to prevent the removal therefrom.

2. An anti-thumbsucking device comprising a pair of substantially parallel relatively rigid tubular members adapted to receive in relatively loose engagement the thumb and index finger of an infant's hand, said tubes being secured together to form an integral unit and each of said tubes having a lower edge defining together a substantially continuous unbroken curve, each of said tubes being substantially less in length than the digit member adapted to be encased, thereby permitting relatively free movement of said digit, the top of said thumb tube terminating substantially short of the top of said index finger tube, each of said tubes being formed with an aperture through the wall thereof oppositely disposed, and being adapted to receive means for securing said tube to the hand of the infant user.
